UNITED STATES PATENT OFFICE

2,509,312

CLOTHESPIN

Arthur C. Orr, West Bath, Maine

Application June 20, 1947, Serial No. 756,026

1 Claim. (Cl. 24—137)

1

This invention relates to new and useful improvements and structural refinements in clothes pins, and the principal object of the invention is to provide a device of the character herein described, which may be conveniently and effectively employed for firmly and securely retaining the clothes on the clothes line.

A further object of the invention is to provide a clothes pin which may be quickly and easily applied and removed.

Another object of the invention is to provide a clothes pin which is simple in construction, which will not easily become damaged, and which will readily lend itself to economical manufacture.

An additional object of the invention is to provide a device of the character described which, in addition to its primary use as a clothes pin, may also be effectively employed for a variety of other uses, such as for example, as a clamp, a paper clip, or the like.

With the above more important objects in view and such other objects as may become apparent as this specification proceeds, the invention consists essentially of the construction and arrangement of parts as shown in the accompanying drawings in which:

Figure 1 is an end view of the invention;

Figure 2 is a top plan view thereof;

Figure 3 is a cross sectional view, taken substantially in a plane of the line 3—3 in Figure 2; and

Figure 4 is an elevational view of the invention, showing the same in position on a clothes line.

Like characters of reference are used to designate like parts in the specification and throughout the several views.

Referring now to the accompanying drawings in detail, the invention consists of a clothes pin designated generally by the reference character 10, the same embodying in its construction a pair of complementary, substantially semi-cylindrical sections 11, the lateral surface of which may be "crowned" as is best shown in Figures 2 and 4.

The opposing flat surfaces 12 of the sections 11 are normally in contact and the adjacent longitudinal edge portions at one side of the sections constitute what may be called a fulcrum, indicated at 13.

2

A pair of coacting handles 14 are secured or formed integrally with the sections 11, the handles 14 being normally disposed in a divergent relation when the surfaces 12 of the sections 11 are in contact.

Means are provided for normally retaining the sections in this contacting position, said means consisting of a pair of arcuate leaf springs 15 which are positioned in suitable, circumferentially extending grooves 16 provided in the end portions of the sections, as will be clearly apparent.

In order to accommodate the clothes line 17 (and the clothes positioned thereon) the sections 11 are provided in the surfaces 12 thereof with longitudinally extending channels 18 which define a substantially cylindrical bore 19 when the sections are in contact. Furthermore, the channels 18 may be so shaped as to provide a plurality of longitudinally extending ribs 20 in the bore 19, for the purpose of firmly and securely gripping the clothes line.

It will be found that the clothes pin may be "opened" by simply pressing the handles 14 together as indicated by the phantom lines 21, during which action the sections 11 will be retracted or spread apart against the resiliency of the springs 15, as indicated at 22. Needless to say, the inherent resiliency of the springs will automatically return the sections to their contacting position, as soon as pressure upon the handles 14 is relaxed.

It should be also pointed out that while two of the springs 15 are illustrated in the accompanying drawings, only one of the springs may be provided, the same being disposed in a suitable groove (not shown) formed medially the length of the two sections, that is to say, substantially where indicated by the lines 23. In such event, the single spring should extend through the handles 14, as will be clearly apparent.

It is believed that the advantages and use of the invention will be clearly apparent from the foregoing disclosure and accordingly, a further description thereof at this point is deemed unnecessary.

While in the foregoing there has been shown and described the preferred embodiment of this invention it is to be understood that minor changes in the details of construction, combina-

tion and arrangement of parts may be resorted to without departing from the spirit and scope of the invention as claimed.

Having described the invention what is claimed is:

In a clothes pin, the combination of a pair of substantially semi-cylindrical gripping jaws having flat surfaces adapted for abutting engagement, longitudinal edges of said jaws at one side of said surfaces being in contact and constituting a fulcrum, a pair of coating handles provided on said jaws at the sides of said fulcrum and extending outwardly therefrom, end portions of said jaws being formed with circumferentially extending grooves having closed ends located in a substantial diametrical opposition to said fulcrum, and resilient bands removably positioned

in said grooves whereby said jaws are held together and the flat surfaces thereof are urged in abutment, ends of said bands being engageable with the ends of said grooves to prevent rotation of the bands on said jaws.
